UNITED STATES PATENT OFFICE.

GEORGE A. LANGMAID, OF HAVERHILL, MASSACHUSETTS.

DESIGN FOR AN EYELET.

No. 37,918.

Specification for Design.

Patented March 27, 1906.

Application filed November 1, 1904. Serial No. 231,023. Term of patent 7 years.

To all whom it may concern:

Be it known that I, GEORGE A. LANGMAID, of Haverhill, in the county of Essex and State of Massachusetts, have invented a certain new, original, and ornamental Design for Eyelets, of which the following is a specification.

Figure 1 is a perspective view of an eyelet designed in accordance with the present invention. Fig. 2 is a plan view thereof.

I claim—

The ornamental design for an eyelet, as shown.

GEORGE A. LANGMAID.
